UNITED STATES PATENT OFFICE.

GEORGE W. ANSLEY, OF SPOKANE, WASHINGTON.

HAMMER.

1,318,826.

Specification of Letters Patent.

Patented Oct. 14, 1919.

Application filed May 15, 1919. Serial No. 297,318.

To all whom it may concern:

Be it known that I, GEORGE W. ANSLEY, a citizen of the United States, residing at Spokane, in the county of Spokane and 5 State of Washington, have invented certain new and useful Improvements in Hammers; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in claw hammers, and the object in view is to generally improve upon and render more efficient the construction of hammer covered by Patent #1,017,491, granted to me upon February 13th, 1912.

20 Experience has developed certain weak points in the construction of the hammer made in accordance with said patent and it is with the view of remedying these 25 defects and render more efficient said hammer that the present invention is produced.

The invention comprises various details of construction, combination and arrangement of parts which will be hereinafter fully described, shown in the accompanying drawings and then specifically defined in the appended claims.

30 My invention is illustrated in the accompanying drawings which, with the numerals of reference marked thereon, form a part of this application, and in which:

35 Figure 1 is a view in elevation of a hammer embodying my improved changes, being cut away to better illustrate certain features 40 of the invention.

Fig. 2 is a top plan view.

Fig. 3 is a detail bottom plan view of two of the jaws, and

Fig. 4 is a detail in elevation showing the 45 manner of operating the claws.

Reference now being had to the details of the drawings by numerals:

1 designates a hammer head which has a tapering recess 2 formed in one end thereof, 50 as shown in Fig. 2 of the drawings, and 3 and 4 designate two supplemental jaws, each having a contracted shank portion 5 and each shank portion terminates in a lug 6, shown clearly in Fig. 1 of the drawings. The inner faces of said jaws, as shown in Figs. 2

and 3 of the drawings, are parallel and in contact with each other up to the point designated by numeral 7, from which location to the ends of the claws the edges 8 are outwardly curved. The outer face of said 60 shank portion of the jaw is inclined and is adapted to contact with a similarly inclined wall in the slot in the head of the hammer, and are designed to have a wedging action against the same as the claws are operated 65 in the act of pulling the nail. Said claws are provided each with an elongated slot 9, and 10 designates a pin passing through said slots and also through registering apertures in the walls of the slot and of the hammer 70 head. The inner end of each shank portion of the jaw is widened and has an abutting surface 10' against which one end of a coiled spring 11 bears, the other end of the spring bearing against the bottom of a 75 recess 12 in the hammer head.

It will be noted upon reference to Fig. 4 of the drawings that the slotted end of the hammer is concaved as at 13 and the inner end of each claw has a convex shoulder 14 80 adapted to have a bearing against said concaved portion 13.

In operation, the coiled spring will tend to hold the parts in the position shown in Fig. 1. When it is desired to grip and pull 85 the nail, the jaws forming the claw end of the hammer is caught underneath the nail and as the hammer is swung through the medium of its handle, the head of the hammer being fulcrumed in the manner shown 90 in Fig. 4 of the drawings, the movement of the claw end of the hammer will be upward, while the claw will have a tendency to be held stationary and moved with the nail which it grips. As the hammer head moves 95 independent of the jaws forming the claws a wedging action will take place intermediate the adjacent faces of the shank portions of the jaws and the wall of the slot in the hammer head, causing the jaws to bind and securely hold the nail, and as the head tilts the shoulders 14 will strike dead against the concaved end of the claw and not slip down and force the jaws outside of the slot in the hammer. Thus I have a trouble experi- 100 enced in the operation of the hammer covered by said patent, and which subjects the parts to a heavy strain, which is obviated by the movement described in the improved form.

By the provision of the pin passing through elongated slots in the shank portions of the jaws, the latter will work up and down upon the pin, permitting the jaws 5 to grip the nail, so that when the convexed shoulders upon the jaws contact with the concaved portions upon the claw end of the hammer, the jaws will move upon the pin at the same time and tend to keep the jaws 10 even at their outer ends. This will enable the points to be readily inserted underneath the head of a nail.

By having the back ends of the jaws widened, the coiled spring may be fitted 15 farther back away from the pin and tend to increase the lifting force of the spring to throw the jaws forward. By the provision of the lugs in the inner ends of the jaws engaging indentures formed in the claw end 20 of the head, the points will be kept even, dispensing with the dowel pin upon which the jaw head has a tendency to work up and down.

What I claim to be new is:

25 1. A claw hammer, comprising a head with a rectangular outlined recess formed in the claw end, the opposite edges of the recess being parallel, slotted claws having their opposite outer marginal edges parallel and engaging said recess, the outer walls of 30 the claws being inclined to conform to the inclined walls of said recess, the forward ends of the claws having pivotal connection

with the bottom of the recess, and a spring 35 for holding the claws at their outer limit.

2. A claw hammer, comprising a head with a recess in the claw end thereof, the bottom of said recess having a notch formed therein, the outer edges of said recess being parallel and the side walls inclined, claws 40 pivotally mounted in said recess and having each a projection at its inner end engaging said notch, the outer walls of the claws being inclined to conform to the inclined walls of the recess, a spring for normally holding 45 the claws at their farthest outer throw.

3. A claw hammer, comprising a head portion the claw end of which is provided with an elongated recess, the marginal edges of which are parallel and the faces inclined, 50 the inner end of the recess having a notch, and a circular outlined recess below the latter, a pin passing through said inclined walls of the recess, claws pivotally mounted to have a slight play upon said pin and provided with constricted projecting portions 55 pivotally engaging said notches, and a spring bearing between the inner end of each claw and the bottom of said circular outlined recess.

In testimony whereof I hereunto affix my signature in presence of two witnesses.

GEORGE W. ANSLEY.
